ENCLOSURE FOR ELECTRONIC EQUIPMENT

Carl J. Clement, Jr., Palo Alto, Calif., assignor to Spectra-
Physics, Inc., Mountain View, Calif., a corporation of
California

Filed June 14, 1965, Ser. No. 85,713

Term of patent 14 years

(Cl. D26—5)

FIGURE 1 is a right side, top and front perspective view of an enclosure for electronic equipment showing my new design;

FIGURE 2 is a right side, bottom and back perspective view;

FIGURE 3 is a front elevational view; and

FIGURE 4 is a fragmentary sectional view taken along line 4-4 in FIGURE 3.

The left side, not shown, is substantially identical to the right side.

The dominant features of my new design are shown in solid lines in the drawing.

I claim:

The ornamental design for an enclosure for electronic equipment, as shown and described.
